R. S. PERSHING

ELECTRIC HEATER FOR OIL WELLS AND THE LIKE

Original Filed Sept. 11, 1920

Patented Aug. 14, 1923.

UNITED STATES PATENT OFFICE.

ROYAL S. PERSHING, OF FORT WORTH, TEXAS.

ELECTRIC HEATER FOR OIL WELLS AND THE LIKE.

Application filed September 11, 1920, Serial No. 409,547. Renewed October 3, 1922. Serial No. 592,135.

To all whom it may concern:

Be it known that I, ROYAL S. PERSHING, a citizen of the United States, residing at Fort Worth, in the county of Tarrant and State of Texas, have invented certain new and useful Improvements in Electric Heaters for Oil Wells and the like, of which the following is a specification.

This invention relates to improvements in devices for heating substances in wells or cavities in the earth in order to create or increase the flow or output of oil, water or the like, and pertains more particularly to a device of this character for use in oil wells where the oil in the bottom of the hole has ceased or partly ceased to flow by reason of paraffine or other ingredients or substances in the oil clogging the oil bearing rock or sand, the prime object being to melt or heat the paraffine or other solids or semi-solid substances by electrical means provided in the form of a heater suspended on the cable or sand line and connected by wires to a source of electric current generated above ground.

Another principal object is to provide a heater comprising a series of interchangeable heater units properly insulated and so arranged that the maximum amount of heat generated and transferred through the wires to the heater may be obtained, and the heat regulated to suit conditions in the well.

Other minor advantages and objects will become apparent as the description of the invention proceeds, reference being had to the accompanying drawings wherein,

Figure 1 is a side elevational view of the heater suspended in a well, the heater receptacle partly broken away.

Figure 2 is a side elevational view in enlarged section with part broken away, of the heater units or cells in the cage.

Figure 3 represents a partial longitudinal sectional view showing the interior of one of the cells or units and its neighboring cells and the mode of connection and their arrangement in the cage.

Figure 4 is a cross-sectional view taken through the cage and receptacle and one of the units, and

Figure 5 is a cross sectional view through the cage showing the contacts and manner of holding the cells in place in the cage.

Referring more particularly to the drawings, 1 represents the wall of a well in which the device is lowered and suspended on the sand line or cable 2. The device or heater comprises a shell or receptacle 3 with an opening at each end and provided with a cap 4, and to the upper cap is connected the sand line or cable 2 and in which are seated the terminal posts 4a.

Inside the receptacle 3 is arranged a cage 5 for supporting and carrying the heater units, each of which consists of a shell or housing 6 and provided with a cap 7. On the cap 7 and likewise the lower end of the shell 6 is a projection 8 between which and abutting the projections is a core 9 around which is wound the heater wire 10, carrying the electric current, supplied from a source generated above ground through the feed wires 11 and 12. The core 9 and projections 8—8 are centrally bored to receive a bolt 13 which is provided to secure the core in the shell 6 and each shell containing the wire wound core 9 is secured in position by a spring 14.

The wire 10 has its ends connected to terminals 15 and 16 so that each heater unit or coil may be connected to its adjacent unit, such connection being made by means of an insulated spring 17 connected to an insulating strip 18, and also connected with a contact screw 19, also properly insulated as shown.

The cells or heat units are thus connected with each other, but where a cell or unit becomes faulty or where a certain number of units only are required any of the units may be removed without breaking the circuit, since each shell or unit is also independently connected with the source of heat by means of rods 20—20 which extend from the top to the bottom of the receptacle 3. The springs 17 are extended beyond the cage 5 and bent downward and connected to the rods 20—20 as shown in Figure 2 and at the top of the receptacle to the feed wires 11 and 12.

The device is supplied with electric current from a source of heat above ground and provided with means commonly in use for controlling the electric current. The receptacle 3 and principal parts are preferably of copper which by its nature will tend to deliver the maximum amount of heat derived from the electric source from the generator.

10 Having thus described the nature and objects of my invention, what I claim as new and desire to secure by Letters Patent, is—

15 1. A heater for oil wells and the like, comprising a tubular receptacle with closures at the top and bottom thereof, means within the receptacle for suspending a plurality of heater coils in spaced unitary relationship, each heater coil encased in a shell and each shell having closures at each end 20 and connecting members and so arranged

that each unit or coil connects with each other and whereby the removal of one or more cells or coils will not interfere with the heating arrangement.

2. A heater for oil wells and the like, 25 comprising a tubular receptacle with closures at the top and bottom thereof, means within the receptacle for suspending in longitudinal or vertical position one upon the other, a plurality of heater units, each unit 30 comprising a wire-wound core enclosed in a shell, said shell having means for connecting or making contact with its neighboring shell to form a continuous multiple battery and said connections or contacts so arranged 35 that removal of one unit or cell will not interfere with the heating arrangement.

In testimony whereof I have signed my name to this specification.

ROYAL S. PERSHING.
